EDWIN LUNDGREN, OF FREDERICK, MARYLAND, ASSIGNOR TO COMBUSTION ENGINEERING CORPORATION, A CORPORATION OF NEW YORK

ART OF BURNING FINELY DIVIDED FUEL

Application filed November 19, 1924. Serial No. 750,723.

This invention relates to the generation of steam by the burning of finely divided fuel, and is especially useful in stationary boiler installations in which the fuel is in the form of pulverized coal.

One of the primary objects of my invention is to increase the rate of evaporation, enabling me to generate a given amount of steam with a boiler of smaller size, or stated in other words, to enable me to develop more steam from a boiler of standard size of given type.

Another object of my invention is for a given output or capacity to generally decrease the size and expense of boiler installations.

To obtain the desired increase in capacity with relative smallness of installation, I propose to define the combustion space of the furnace chamber very largely by the heat absorbing surfaces of the boiler, so that the latter will be subject to radiant heat and, therefore, perform at a very high rate.

With such an arrangement, however, by reason of the great absorption of the heat absorbing surfaces, there will be a considerable chilling effect on the furnace temperature, and I therefore propose to add heat, or rather introduce heat to the combustion space to properly support combustion.

I further propose to obtain this additional heat by providing such a relation, in regular operation, between the rate of fuel feed, the amount of heat absorbing surface and the time interval for the combustion of the fuel in the combustion space, as to obtain a temperature of the gases leaving the combustion space sufficiently high to permit me to extract the required amount of heat for introduction to the combustion space.

How the foregoing, together with such other objects, as may hereinafter appear, or are incident to my invention, are realized, is illustrated in the preferred form in the accompanying drawings wherein;

Fig. 1 is a vertical section thru an installation embodying my improvements;

Fig. 2 illustrates one form of burner which may be employed in carrying out my invention;

Fig. 3 illustrates a modified form of burner. Referring now to Fig. 1, A represents the

combustion chamber, having an outlet 6 in the upper part thereof, over which there is arranged a part of the boiler to be hereinafter described. The rear portion of the side walls of the combustion chamber are covered with water walls 7, and the bridge wall is covered by a water wall 8, such water walls being composed of tubes preferably provided with fins arranged to overlap. The water walls 7 and 8 cooperate to define a portion of the combustion space. The bottom of the combustion space is defined by a screen 9 composed of suitably spaced tubes extending across the lower portion of the combustion chamber. The water walls and the screen are connected into the circulation of the boiler in the manner shown.

The forward portions 10 of the side walls of the combustion chamber and the front wall 11 of such combustion chamber are composed of refractories and are not protected by heat absorbing surfaces, in the preferred embodiment of my invention.

Fuel is admitted in an upper part of the combustion chamber in a downward direction in the space defined by the refractories, thru the medium of a plurality of burner nozzles B, arranged in a row transversely of the chamber. The fuel and flame stream takes a downward course and then reverts in U form as the downward momentum is overcome.

The boiler over the outlet and in the off-take comprises the two spaced sections or banks of tubes C and D, between which are located the superheater elements E and air heater F the baffling being such that the gases take the course through the offtake and to the stack indicated by the arrows.

Air is supplied to the heater F, which consists of a plurality of pipes or tubes (preferably treated to withstand high temperatures), by the pipe 12 and fan 13, and is conducted therefrom by the pipe 14 to a manifold 15 which is provided with outlet and discharge casings 16, one around each nozzle.

The coal is supplied to the burners, preferably with carrying air and the entering fuel streams are surrounded by the preheated air supplied around the nozzles. This preheated

air is not sufficient for combustion and the balance required is preferably supplied at successive levels through the front wall by rows of inlets 17. This air is also preferably 5 preheated, to which end I locate a heater G in the stack through which air is drawn by the fan 18 and supplied to a manifold 19 common to the inlets 17.

In regular operation the rate of fuel feed, 10 and the rate of withdrawal of the gaseous products with reference to the heat absorbing surface is such that, while heat must be added to further proper combustion, yet the gases leave at a comparatively high temperature 15 and carry sufficient heat for the abstraction of the necessary heat for return to the combustion space; this with combustion completed in the combustion space. The air heater F, being located just beyond the first 20 section of the upper part of the boiler, is subjected to the very hot gases and the air passing therethrough is heated to a high degree, from 400° to 700° or more. This hot air surrounding each entering fuel stream and 25 mingling therewith by virtue of eddying, due to difference in velocity, the construction of the burners and the like, immediately institutes ignition with the aid of the radiant heat from the refractories. It and the 30 radiant heat and the hot air admitted through the front wall expedite combustion and carry it well forward before the general fuel and flame stream turns into that portion of the combustion space defined by the tubes, and 35 the heat from the forward portion of the chamber and from the burning fuel therein maintains proper combustion throughout the combustion space. Thus the chilling effect of the tubes is overcome. While the 40 gases leave at a high temperature, the final exit temperature is kept within allowable limits because of the further abstraction of heat in the stack.

By admission of air at right angles to the 45 plane of fuel delivery eddying is set up ensuring proper admixture.

In case difficulty is encountered with "coking" at the nozzles, the preheated air may be supplied according to the arrangement of 50 Fig. 3, in which the manifold 15^a is provided with pairs of delivery channels 16^a, one on each side of the nozzles. By this arrangement, the nozzles are not heated to the same degree, but nevertheless the fuel is immediately subjected to highly heated air and 55 eddying is quickly instituted by the impingement of the hot air and the coal.

I claim:

60 In a pulverized fuel burning boiler furnace, a combustion chamber having a substantial portion of its combustion space defined in part by non-metallic refractory walls and in part by water containing walls, burner means for admitting the fuel in the region 65 defined by the refractories, said chamber

having an offtake for the products of combustion, boiler tubes in said offtake subject to the products of combustion, air heater means in the offtake adapted to supply preheated air to the burner means, and a stack 70 for the waste gases, together with air preheater means in the stack and means whereby preheated air therefrom is supplied to the combustion space.

In testimony whereof, I have hereunto 75 signed my name.

EDWIN LUNDGREN.
